UNITED STATES PATENT OFFICE.

XURRY H. WISELL, OF TORRINGTON, CONNECTICUT.

NONSKID HORSESHOE.

Application filed March 20, 1923. Serial No. 626,297.

To all whom it may concern:

Be it known that I, XURRY H. WISELL, a citizen of the United States, residing at Torrington, county of Litchfield, State of Connecticut, have invented a new and useful Nonskid Horseshoe, of which the following is a specification.

It is an object of the invention to provide a horseshoe with an improved nonskid tread, and to also provide improved means for securing this tread to the shoe, which will allow ready attachment and removal of the tread without removing the shoe from the hoof, so that should the tread become worn or broken it may be quickly renewed at low cost, and also should the tread be worn faster on one side of the hoof than on the other it may be quickly and easily reversed.

It is a further object of the invention to provide a shoe of this type which will be self cleaning and so will not ball.

It is a still further object of the invention to provide an improved horseshoe tread which will have great gripping powers on the road.

With the foregoing and other objects in view I have devised the construction illustrated in the accompanying drawing, in which—

Fig. 1 is a bottom plan view of my improved horseshoe.

Fig. 2 is an end view thereof, looking from the right of Fig. 1 with a portion of the shoe broken away to more clearly show the construction.

Fig. 3 is a detailed side view of the inner edge of one side of the shoe looking in the direction of the arrows 3—3 in Fig. 1.

Fig. 4 is a transverse section substantially on line 4—4 of Fig. 1, and Fig. 5 is a side view and a cross section of a portion of a rod forming the links and on a somewhat enlarged scale.

The shoe comprises a body member 10 preferably curved to substantially U-shape in the usual manner, this body being substantially flat on top to rest against the bottom of the hoof, and it is provided with the usual countersunk nail-holes 11 for passage of the nails for securing the same to the hoof. The body is also preferably provided at the front thereof with the usual toelip 12. This body member is also provided with a laterally, that is downwardly when secured to the hoof, extending rib or flange

13 about the inner edge thereof, and this flange is also preferably inclined outwardly, as shown, to facilitate cleaning of the shoe and prevent snow and other material clinging thereto and balling. About the outside of this flange I secure my improved tread which comprises a flexible chain 14, the links of this chain being preferably twisted links as this type of link may be more readily secured to the body of the shoe and also each link provides a bearing portion. These links, besides being twisted, are also preferably made of twisted polygonal metal rods so as to provide edges indicated at 15 extending spirally around the rods of the link. This construction greatly increases the tractive, holding or gripping effect of the link on the road surfaces as will be apparent.

I have also provided improved means for detachably securing this flexible chain tread to the body. For this purpose I provide the rib or flange 13 adjacent one end thereof with a hook 16 extending substantially parallel with the plane of the body and adapted to engage one of the end links indicated at 17 of the chain. At the other end of the shoe body I provide a somewhat similar hook 18 adapted to engage the other end link 19, and between these two hooks I provide outwardly extending intermediate hooks 20 engaging certain of the intermediate links of the chain. The number of hooks may vary as is found desirable for securely fastening the chain in position. These hooks extend outwardly over the lower bars 21 of the links, and as the links are twisted the other bar is outside the hooks and so takes all the pressure and protects the hooks, the hooks extending between the two bars as clearly shown in the drawing. To facilitate ready attachment and removal of the flexible chain tread, one of the end hooks, in the present instance hook 18, is so mounted that it may be moved downwardly, that is laterally, away from the body, and for this purpose, it is, in the present instance, carried by a member 22 which is pivoted to the inner wall of the flange 13 by means of a rivet 23. This member also carries a lug or rivet 24 adapted to seat in an opening or recess 25 in the flange 13 to hold the same in securing position, as shown in Figs. 1 and 3. The member 22 is preferably of heavy spring metal and adapted to have its free end flexed inwardly by a suitable tool an amount to disengage lug 24 from the recess 25. The ele-

ment 22 may then be swung about its pivot 23 to move the hook 19 away from the body member to substantially the dotted line position shown in Fig. 3. The flexible chain tread may now be easily applied to the body member, the operation involving merely engaging the end links 17 over hook 16, laying the chain about the outside of the flange 13 in the angle between this flange and the body member with the intermediate hooks 20 engaging intermediate links and then placing the other end link 19 over the hook 18. The element 22 and the hook 18 may now be pressed against the body member to the position shown in full lines Figs. 1 and 3, and the lug 24 by engaging recess 25 will securely hold them in this position. This movement of the hook 18 will tighten the chain sufficiently that it will not disengage from the hooks and will be securely fastened to the body member thereby. The flange 13 is preferably provided with a notch 26 for passage of the hook 18 so as to brace this hook and protect it. If after use, the chain tread should become worn or broken it may be easily removed by raising the hook 18, and disconnecting the end link 19 therefrom when the chain may be easily removed from the other hooks and a new chain applied as above described, or should the sides of the chain be worn unequally it may be easily reversed to correct this. Also after one of the side bars of the links are worn the chain may be easily turned over to use the other bars of the links for the wearing portion.

It will be clear from an inspection of Figs. 2 and 4 that the links are of sufficient width to extend below the free edge of flange 13 so that the weight of the horse is carried by the links. The links should preferably not be so tightly secured to the body member as to have no movement thereon in use, but they should be sufficiently loose that they will have some movement relative to the body and also relative to each other to loosen snow, dirt, stones, and so forth, which may be picked up, and allow them to drop from the shoe so that it will be self cleaning.

It will be apparent from the foregoing description that I have devised a simple and effective horseshoe which will have a very great holding or gripping effect on the road surface, and also one in which the tread may be quickly renewed at low cost without the necessity of removing the shoe from the horse and attaching new shoes, and therefore, they will be less expensive besides being more effective.

Having thus set forth the nature of my invention, what I claim is:

1. A horseshoe comprising a body adapted to be secured to a hoof and provided with a series of hooks, and a flexible chain tread

secured to the body by said hooks, a hook engaging one of the end links of the chain being movable laterally of the body to allow application and removal of the tread without bending the hooks.

2. A horseshoe comprising a body adapted to be secured to a hoof, a flexible chain tread, said body being provided with a series of hooks engaging the links of the chain to secure the same to the body, and a member pivoted to the body and provided with a hook engaging one of the end links of the chain, said pivoted member being adapted for movement laterally of the body to release said end link.

3. A horseshoe comprising a curved body member adapted to be secured to a hoof and provided with a laterally extending flange about the inner edge thereof, a flexible chain tread extending about the outside of said flange and resting against said body, said chain projecting beyond the free edge of the flange to form the tread of the shoe, and means for securing said chain to the body.

4. A horseshoe comprising a body adapted to be secured to a hoof and having a laterally extending rib or flange adjacent one edge thereof, a flexible chain tread in the angle between the body and flange and projecting beyond the free edge of the flange to form the tread of the shoe, and means for securing the chain to the body.

5. A horseshoe comprising a curved body member adapted to be secured to a hoof and provided with a laterally extending flange about the inner edge thereof, a flexible chain tread extending about the outside of said flange, and means for securing the chain to said body including hooks adjacent the ends of the flange to engage the end links of the chain and intermediate hooks engaging other links of the chain, and a member pivoted to the flange and carrying one of said end hooks, said member being movable laterally away from the body to allow disconnection of the hook from the chain.

6. A horseshoe comprising a curved body adapted to be secured to a hoof, a flexible chain tread following substantially the curve of the body and comprising a plurality of connected links, and means for securing said tread to said body, the links of said chain comprising polygonal rods twisted about the axis of the rod to provide each link with a plurality of spiral edges extending transversely across the portion of the link which engages the roadway.

7. A horseshoe comprising a curved body member adapted to be secured to a hoof and provided with a laterally extending flange about the inner edge thereof, a flexible chain tread comprising a plurality of connected twisted links extending about the outside of said flange and projecting beyond the free edge of said flange to form the tread.

of the shoe, the links of said chain comprising twisted polygonal rods, and means for detachably securing the tread to said body.

5. 8. A horseshoe comprising a body adapted to be secured to a hoof and provided with a flange extending laterally at an angle to the body, a flexible chain tread comprising a plurality of connected links embracing said flange and positioned in the angle between the flange and body, hooks extending laterally outward from the flange and projecting into certain of said links, the hook at one end of the chain being pivoted to the flange and movable away from the body in substantially the plane of the flange to release the chain.
9. A horseshoe comprising a body adapted to be secured to a hoof and provided with a flange extending laterally at an angle to the body, a flexible chain tread comprising a plurality of connected links embracing said flange and positioned in the angle between the flange and body, hooks extending laterally outward from the flange and projecting into certain of said links, a resilient support pivoted to said flange adjacent one end

thereof and carrying one of said hooks, said support being movable to allow said hook to swing outwardly away from the body in substantially the plane of the flange to release the chain, and a coacting projection and recess carried by the flange and support to retain the support in its inner position.

10. A horseshoe comprising a curved body member adapted to be secured to a hoof and provided with a laterally extending flange adjacent the inner edge thereof, a flexible chain tread extending about the outside of said flange, said chain comprising a plurality of connected twisted links, and the links comprising twisted polygonal rods, and means for securing the chain to said body including hooks adjacent the ends of the flange to engage the end links of the chain and intermediate hooks engaging other links of the chain, and a member pivoted to the flange and carrying one of said end hooks, said member being movable laterally away from the body to allow disconnection of the hook from the chain.

In testimony whereof I affix my signature.

XURRY H. WISELL.
